CYLINDRICAL BODY RAM

Alexander W. McPherson, 30012 Briarton,
Farmington, Mich. 48024

Filed Aug. 11, 1970, Ser. No. 24,425

Term of patent 14 years

Int. Cl. D15—99

U.S. Cl. D55—1

FIG. 1

FIG. 2

FIG. 3

FIG. 4

FIG. 1 is a perspective view of a cylindrical body ram showing my new design;

FIG. 2 is a side elevation of the cylindrical body ram;

FIG. 3 is a top elevation of the cylindrical body ram;
FIG. 4 is a bottom elevation of the cylindrical body ram.

I claim:

The ornamental design for a cylindrical body ram, as shown and described.
